UNITED STATES PATENT OFFICE.

HUGH McCABE, OF LAWRENCE, MASSACHUSETTS.

OIL-HEATER.

1,099,989.

Specification of Letters Patent. Patented June 16, 1914.

Original application filed December 30, 1912, Serial No. 739,249. Divided and this application filed March 27, 1913. Serial No. 757,108.

To all whom it may concern:

Be it known that I, HUGH McCABE, a citizen of the United States, residing at Lawrence, in the county of Essex and State 5 of Massachusetts, have invented certain new and useful Improvements in Oil-Heaters; and I do hereby declare the following to be a full, clear, and exact description of the invention, such as will enable others skilled 10 in the art to which it appertains to make and use the same.

The present invention relates to furnaces.

The object of the invention is to produce a furnace, preferably portable, which is particularly adapted for heating the edges of 15 plates in preparation for flanging them.

To this end the present invention consists in the furnace hereinafter described and particularly pointed out in the claims.

20 In the drawings which illustrate the preferred embodiment of the invention, Figure 1 is a side elevation of the furnace; Fig. 2 is a plan; and Figs. 3 and 4 are a plan and a sectional elevation, respectively, of the 25 furnace with the cover removed.

The present invention is a division of an application filed December 30, 1912, Serial No. 739,249, oil heaters.

Referring to the drawings, the furnace, 30 indicated generally by reference numeral 1, is mounted on a carriage 2. The carriage 2 is provided with wheels 3 and a handle 4 so that it can easily be wheeled about. The crude oil for use in the furnace is carried 35 in the oil tank 5 mounted on the carriage. Compressed air is supplied to the air connection 6 by any convenient means such as a flexible air hose. The compressed air is admitted by means of a valve 7 through a 40 flexible pipe 8 to the oil burner indicated generally by reference numeral 9. Compressed air is admitted from time to time to the tank 5 by means of a valve 10 to maintain pressure on the oil which is forced up 45 from the bottom of the tank through a pipe 11 through the oil cut-off valve 12 and through the flexible pipe 13 to the oil burner 9. A pressure gage 14 is provided to indicate the pressure maintained on the oil 50 in the tank 5.

The furnace 1 is provided with four laterally extending lugs 20 which are slidably received in two vertical slots 21 in the carriage. To one of the top lugs 20 is connected a link 22 which at its lower end is

connected to a hand lever 23 by means of which the furnace 1 is elevated and lowered. As shown in Fig. 1, the furnace is in its lowered position. When the furnace is raised, the lever 23 is turned upwardly and to the right, as viewed in Fig. 1, until it contacts with a stop lug 24 on the carriage, in which position the connection between the link 22 and the lever 23 is carried a little beyond a dead center position so that the 60 furnace is held in its elevated position. 65

The furnace 1 consists of a metal shell 30 having a refractory lining 31, a cover 32 and the oil burner 9. The shell 30 acts as an inclosing and strengthening support for 70 the refractory lining 31 of fire-brick or like material. In the top of the furnace is an open-topped chamber 33 for the reception of the work to be heated. A flue 34 extends through the bottom of the furnace for the 75 passage of the flame shot upward from the oil burner 9. The oil burner 9 is mounted on the bottom of the shell 30 by means of a bracket 35 so that it is raised and lowered with the furnace. The cover 32 is hinged at 80 36 to two bars 37 which are secured to the shell 30 by means of bolts 38. The bolts 38 pass through elongated slots 39 in the bars 37 so that the bars 37 can be raised or lowered to accommodate plates of different 85 thickness under the cover.

The furnace illustrated in the drawings is adapted particularly for heating the corners of rectangular plates preparatory to flanging the corners. The straight edges of the plates 90 are first flanged through an angle of about 90 degrees, preferably by means of the flanging machines shown in the patents to Hugh McCabe, Nos. 1,030,416 and 1,006,861. The straight edges can ordinarily be flanged cold 95 up to the corners of the plates. The corners must, however, be heated so that the surplus metal can flow when the corner is flanged. A machine for flanging the corners of plates is shown as a modification in my co-pending 100 application Serial No. 728,355, filed October 29, 1912. The plates as presented to the heater preparatory to flanging their corners have their straight edges flanged and the surplus metal at the corners is buckled and 105 left in a sort of rounded fold which extends out from the corner in a direction inclined to the plane of the plate. To receive the corner of the thus partially flanged plate, the chamber 33 has the peculiar shape which 110

is shown best in Fig. 3. The main part of the chamber 33 which is directly over the flue 34 is substantially rectangular in outline and receives the fold of metal left at the corner which must be heated before it can be pressed into shape to form a finished flanged corner. Extending from the main or middle part of the chamber 33 to the outer edge of the furnace 1 are two open-topped slots 10 40 in which are received the down-turned flanges on the straight sides of the plate adjacent to the corner. The plates to be flanged are ordinarily hung by fall and tackle at the correct height for the flanging machine to operate upon them. Before a corner is flanged, the oil heater is rolled under the plate which is swung so that the corner lies above the heater. The handle 23 is then raised and the furnace 1 is lifted beneath the plate and the bent metal at the corner is received in the rectangular portion of the chamber 33 and the down-turned edges fit into the open-topped slots 40. Then the cover 32 is turned from the dotted line 20 position shown in Fig. 1 to the full line position to cover the top of the plate and so confine the heating flame. The flame is then turned on until the corner is heated, after which the cover 32 is lifted, the handle 23 is lowered and the plate is free to be 30 swung into the flanging machine.

While the preferred embodiment of the present invention has been specifically illustrated and described, it is to be understood that the present invention is not limited to the illustrated embodiment of the invention, but may be embodied in other structures within the scope of the invention as defined in the following claims.

40 I claim—

1. An oil heater for heating the corners of plates, the straight edges of which have been already flanged, having, in combination, a furnace comprising an oil burner, an

open-topped chamber for receiving the partially bent corner, said chamber having open-topped slots extending to the outer edge of the furnace for receiving the flanged straight portions of the edge and a cover for the chamber to cover the top of the plate, and means for elevating the furnace so that it may be raised beneath the corner of the plate, the partially flanged corner and flanged straight edges of the plate fitting into the open-topped chamber and the open-topped slots, substantially as described.

2. An oil-heater for heating the corners of plates the straight edges of which have been already flanged, having, in combination, a wheeled carriage for moving the heater beneath the corner of a plate, a furnace slidingly mounted to be raised or lowered in the carriage, comprising an oil burner, an open-topped chamber in the top of the furnace for receiving the partially flanged corner, 65 said chamber having open-topped slots disposed at an angle to each other and extending to the outer edge of the furnace for receiving the flanged straight portions of the plate edge, a flue for directing the flame 70 from the oil burner into the chamber, and a cover for the chamber to cover the top of the plate and confine the flame, and means for lifting the furnace so that it may be raised beneath the corner of the plate including a 75 lever and link connected between the furnace and the carriage and having the pivotal connection between them carried a little beyond dead center position when the furnace is elevated so as to hold it in elevated position, the partially flanged corner and flanged straight edges of the plate fitting into an open-topped chamber and the open topped slots respectively, substantially as described.

HUGH McCABE.
